UNITED STATES PATENT OFFICE.

ROBERT J. BLACK, OF KANSAS CITY, KANSAS.

PROCESS OF PRESSURE DISTILLATION.

Application filed April 30, 1921. Serial No. 465,874.

To all whom it may concern:

Be it known that I, ROBERT J. BLACK, a citizen of the United States, residing at Kansas City, in the county of Wyandotte and State of Kansas, have invented certain new and useful Improvements in Processes of Pressure Distillation, of which the following is a specification.

The process of pressure distillation to which my invention relates has for its object the cracking or splitting up of heavier hydrocarbons, such as are contained in gas oil and crude petroleum, for the purpose of forming gasoline or other lighter or more volatile products. For this purpose the oil is heated to a high temperature under a pressure, ordinarily of four or five atmospheres, with the result that certain of the hydrocarbons constituting the gas oil or the like are broken down and vaporized, the vapors thereof being collected and condensed and further treated for the purpose of forming a commercial gasoline. The apparatus commonly employed for this purpose comprises an externally heated still drum or shell in which the oil is heated under pressure to the cracking temperature and from which the vapors formed are led to a tower in which the heavier hydrocarbons are condensed, the lighter hydrocarbons forming the desired distillate passing by a vapor-line to a condenser and thence to a run-down-drum or condensate receiver. The latter is commonly provided with a connection by which the fixed gases, formed during the distillation are led away or permitted to escape.

The use of the method commonly employed today results in the formation, in addition to the gasoline, of free carbon or coke and non-condensable or fixed gases. The carbon or coke is drawn off with the heavier residue from the operation, constituting practically a waste product and the fixed gases are ordinarily burned or a certain proportion of them absorbed in heavy oil. These fixed gases ordinarily constitute from two to ten per cent of the product and are practically a refining loss. It is the purpose of my invention to utilize these non-condensable gases, returning them to the still, incorporating them with the distillate chemically, thereby increasing the amount and improving the quality of the gasoline produced, and making pressure distillation a more profitable method of manufacture.

With this end in view I pipé the non-condensable or fixed gases from the condensate receiver of the pressure still direct to a low pressure receiver tank; the latter in connected to the suction side of a power-driven compressor and the exhaust side of the latter is connected to a perforated pipe or system of pipes located in the bottom or other portion of the pressure still where the oil is in direct contact with the highly heated wall thereof and where cracking of the oils and vapors, consequently, largely takes place. The fixed gases containing a large amount of available hydrogen being thus injected into the oil under pressure and into direct contact with the hydrocarbons including the newly formed or nascent unsaturated hydrocarbons, supply the latter with hydrogen so that a larger proportion of saturated and more nearly saturated hydrocarbons are formed. Moreover, by thus saturating the oil in the region of active decomposition and recombination with highly compressed fixed gases the further formation of the latter is opposed under the well-known law of mass action, while permitting and assisting the formation of the more desirable hydrocarbons.

In the accompanying drawing I have shown and in the following specification described a preferred form of apparatus for practicing my invention; it is to be understood, however, that the invention is not limited to the specific form of apparatus employed, nor to the particular type of still shown, it being applicable to substantially all shell types of pressure stills.

In the accompanying drawings Fig. 1 is a partially diagrammatic side elevation of a still with its connections, embodying my invention; Fig. 2 a plan view showing two of the units of a battery of such stills, partly broken away to show their construction; Fig. 3 a front elevation thereof; Fig. 4 a transverse section of a still embodying my invention, on an enlarged scale; Fig. 5 a longitudinal vertical section through such still showing a specifically different form of tower and run-back; Fig. 6 an enlarged diagrammatic view of a compressor and its connections; and Fig. 7 a similar view of a preferred form of release manifold.

Each part is identified by the same reference character wherever it occurs in the several views.

My invention being applicable to shell

stills in general, I have chosen to illustrate it in connection with a well known form of equipment, the essential elements of which I will now proceed to briefly identify, it being observed that the several units of the battery of stills partially shown are substantially identical and therefore a description of one will suffice for both. The still shown is of the shell type, and comprises a retort or shell 6, furnace setting 7 and tower 8. The shell is provided with a safety valve 5 to prevent excess pressure therein and a draw-off 6 for emptying the still. In the form of the device shown in Figs. 1 to 15 inclusive the tower is supported by framework 9 and connected to the shell or still proper by the main vapor line 10, and from the upper end of the tower a vapor-line 11 descends to a T 12 connected on the one side by an auxiliary run-back 13 to the main run-back 10 and on the other side by the vapor-line 14 to the condenser 15. On its way to the condenser this vapor-line is carried through the pressure control house 16 where it is provided with pressure-gauge and valve regulation. Each condenser is connected by a run-down line 17 with a run-down drum 18 to receive the condensate and the run-down drums are connected to a common gas-line 20 by pipes 19, 19, by which the fixed gas is led away from such drums. As thus far described the construction is of a common and well known character.

In the apparatus which I have devised for carrying out my invention the low-pressure gas-line 20 conducts the fixed gas to a gas receiver 21. The gas receiver is connected by pipes 22 to the intakes of compressors 23, respectively, and the outlets of the latter are connected by pipes 24, respectively, to a high pressure gas-line 25 by which the fixed gas, after being compressed, is conducted to a manifold 26. Manifold 26 extends over the drums of the battery and is formed or provided with a series of branch pipes 27 through which the fixed gases are led to pipes 28 located in the bottoms of the shells and perforated so as to inject the gases into the liquid and against the bottom of the still over substantially all of the heated area thereof. The perforated pipe 28 may be duplicated or multiplied in the still.

In case it is desired to introduce steam with or without the fixed gas, I have shown at 29 a steam pipe which is connected at 30 to the manifold.

The operation of the apparatus will be apparent from the above description thereof. The vapors and gases developed in each still pass through the main vapor line to the towers, in which, as usual, the heavier hydrocarbons which are not light enough to be included in the desired distillate are con-

70 densed and returned to the still. From the upper end of the tower the vapors which are to form the distillate together with what fixed gases are formed pass by vapor-lines 11, 14 through the pressure control house 75 and to the respective condensers. From the condensers the condensate and the uncondensed gases pass to the run-down drums 18 from which the fixed gases are delivered by pipes 19, 20 to the gas receiver 21. The 75 pipes 19 connecting the run-down drums with the low pressure pipe 20 are provided with suitable valves 19^a by which the pressure in the still system may be controlled.

80 From the gas receiver 21 the gases are drawn by the compressors and after being put under a pressure in excess of that in the stills are forced through the common gas-line 25, manifold 26, and branch pipes 27, to the perforated pipes 28 in the respective stills. The gas issuing under high pressure and with great velocity from the perforated pipe is directed against or towards the bottom of the still and particularly towards those portions thereof which are most highly heated. The gas thus introduced performs both a chemical and a mechanical function. The heated oil in the region of greatest chemical activity is saturated with the fixed gas whereby the formation of additional quantities of such gases is opposed. Moreover, the presence of the hydrogen contained in such gases in the reaction zone increases the saturation of the product formed by uniting therewith. The gases act in a mechanical manner to improve the product by producing a rapid circulation of the oil and tarry matter in contact with the hottest portion of the walls of the retort, thus tending to prevent the formation of carbon and washing away deposits thereof as they occur, cooling the wall of the still by the circulation of the liquid in contact therewith, thus preventing overheating and burning of the still and development of hot-spots and local overheating. By the continuous introduction of the fixed gases stratification of the gases and vapors within the still is prevented.

100 By my improved method of operation the proportion of distillate of the desired composition is increased and its quality improved, the distillate produced being nearer to water-white in color and easier to keep than ordinary pressure distillate. Moreover, my improved method of gas injection and circulation renders the control of the pressure in the still positive and easy, and it is possible to maintain a materially higher pressure with the same firing of the 105 still. It will be observed, moreover, that the gas receiver floats on the low pressure line and equalizes fluctuations on the low pressure side. In carrying out the invention it is advantageous in addition to the 110

fixed gas produced by the still to introduce other gases rich in hydrogen, such for example, as natural gas. For this purpose I provide a connection 40 with a valve 41 for introducing such gas into the gas receiver.

The tower 8 and vapor line 11 shown in Fig. 1 are of a round type. I prefer however, to employ the form of apparatus shown in Fig. 5 which may readily be substituted for that of Fig. 1. The tower 8^a is shown as connected to a drum 42 on the still by a run-back 43. The vapor line 44 is connected into the top of the tower and comprises a cross member 45 and a down-comer 46. The latter is surrounded substantially throughout its length by and extends to near the bottom of a cylinder or tube of larger diameter 47, the lower end of which is contracted or headed at 48 for connection to a pipe 49 which extends into the still drum and nearly to the bottom of the latter. The upper end of the cylinder or enlarged pipe 47 is closed at 50 and a vapor line 51 extends therefrom to the condenser.

By means of the construction just described, any fine drops or particles of condensate formed in the tower and such condensate as is formed in the pipes, 44, 45 and 46 is returned to the drum. The vapors containing such condensate flow downward through tube 46 at considerable speed and emerging from the lower end of pipe 46 into cylinder 47 passing upwardly therein to the vapor line 51. The heavier drops of condensate however, through their inertia are carried down to the bottom of the cylinder 47 and passed by pipe 49 to the body of the liquid in the drum. By this construction and by properly proportioning the parts and pressure of regulation it is possible to much more accurately separate the heavier hydrocarbons from those which are light enough to form part of the desired distillate.

The compression and return of the gas from the low pressure to the high pressure line may be regulated by controlling the speed of the compressor. In practice however, I have found it more convenient and practical to effect the control of the return of the gas to the still drum without resorting to regulation of speed of the compressors by means of a connection shown in Fig.

6 of the drawing. In said figure the compressor is diagrammatically represented at 23^a, the compressing cylinder being shown at 52. In this arrangement of parts the pipe 22^a from the receiver is branched at 53, one branch 54 being connected to the intake side of the compressor. The exhaust side of the compressor is connected by pipe 24^a to the high pressure line. The other branch 55 from the low pressure line constitutes a by-pass about the compressor and is connected at 56 to the high pressure line 24^a. Hand valves 57, 58 are included in the respective branches, and a pressure gauge 59 is included in the by-pass. By manipulation of the hand valves 57, 58 the amount of gas that passes through the compressor may be regulated and excess gas delivered by the compressor returned to the low pressure line. Thus the valve adjustment of the speed of the compressor and the amount of gas returned to the still drum may be regulated as required, the pressure gauge informing the operator of pressure conditions with in the line.

In Fig. 2 I have indicated diagrammatically the valves 19^a which control the pressure in the run-down drums. I prefer, however, for accuracy of adjustment to use the construction shown in Fig. 7. Instead of employing a single valve I provide a plurality of needle valves 60, here shown as three in number, connected across the headers 61, 62. It will be obvious that these valves may be of smaller capacity than a single valve for controlling the same flow and more accurate regulation is therefore possible.

I claim:

A process of making gasoline and the like, consisting in heating a body of heavier hydrocarbons at a cracking temperature under pressure in an externally heated shell still, and continuously injecting highly compressed still gases, enriched with gases containing a large amount of available hydrogen, against the most highly heated surface of the still shell with which the liquid is in contact, that is into the region of most active decomposition, and over substantially all of the heated area thereof.

ROBERT J. BLACK.
